UNITED STATES PATENT OFFICE

109,332

DESIGN FOR A BUCKLE

Edwin S. Mix, Rochester, N. Y., assignor to
Hickok Manufacturing Company, Inc., Rochester, N. Y., a corporation of New York

Application November 4, 1937, Serial No. 72,623

Term of patent 3½ years

To all whom it may concern:

Be it known that I, Edwin S. Mix, a citizen of the United States, residing at Rochester, in the county of Monroe and State of New York, have invented a new, original, and ornamental Design for Buckles, of which the following is a specification, reference being had to the accompanying drawing, forming part thereof.

In the drawing:

Figure 1 is a perspective view of a buckle showing my new design.

Figure 2 is a longitudinal sectional view taken on the line 2—2 of Figure 1.

The design comprises two rings arranged in

fixed relation one upon the other in approximately parallel planes, the lower ring being disposed in advance of the upper ring and provided at the front with a depending L-shaped lug extending downwardly from the lower face of the forward ring centrally of the front portion thereof. The front portion of the lower ring defines a crescent shaped panel and the upper ring presents a complete unbroken circular figure.

I claim:

The ornamental design for a buckle, as shown and described.

EDWIN S. MIX.
